L. J. BARGER

DOOR CLAMP

Filed Aug. 14, 1923

Fig. 4.

Lewis J. Barger
INVENTOR
BY Reg. T. Rauher
his ATTORNEY

UNITED STATES PATENT OFFICE.

LEWIS J. BARGER, OF MAPLEWOOD, NEW JERSEY.

DOOR CLAMP.

Application filed August 14, 1923. Serial No. 657,314.

To all whom it may concern:

Be it known that I, LEWIS J. BARGER, a citizen of the United States, residing at Maplewood, in the county of Essex and State of New Jersey, have invented certain new and useful Improvements in Door Clamps, of which the following is a specification.

This invention relates to a door clamp or auxiliary vise, and, more particularly, to a clamp for holding doors when fitting them and cutting out for hinges preparatory to hanging them in door frames and for holding other objects for similar purposes.

In fitting doors heretofore, it has been customary to hold the door in an upright position in the door opening by means of wedges or a wedge structure which is hammered together about the door and, after the work is completed, is knocked apart. The wedging of the doors in this manner requires considerable work and involves some difficulties and, in addition, is not entirely satisfactory or convenient in use.

An object of the present invention is to provide a holding device that may be readily and quickly set up to hold a door or other object rigidly in vertical position convenient for fitting or planing.

Other objects of the invention are to provide a holding device of this type which is of simple and unitary construction adapted to be carried in a tool chest and to provide a clamping device or auxiliary vise which may be readily adjusted to clamp doors or objects of various thicknesses.

With these and other objects in view, the invention comprises the device described and set forth in the following specification and claims.

The various features of the invention are illustrated in the accompanying drawings, in which,

Fig. 1 is a side view of a clamping device embodying a preferred form of the invention, the device being shown in outline in dotted lines in clamping position on a door also indicated in broken lines,

Fig. 2 is an end view of the clamping device of Fig. 1 in clamping or holding position on a door,

Fig. 3 is a detail sectional view of the clamping device taken on line 3-3 of Fig. 1, and,

Fig. 4 is a detail view of a portion of a

spring element forming part of the clamping device.

In the present invention the door or other object to be held is placed between a pair of clamping blocks which are held in spaced relation at a distance from each other equal to the width of the door by a holding means at the lower edges of the blocks. This holding means also acts as a spring to hold the blocks slightly tilted on their farther corners or edges so that the opposing vertical faces of the blocks diverge slightly upwardly to permit the door to be placed therebetween. When the weight of the door bears downwardly on the spring holding element, the blocks turn on their farther edges, which rest on the floor, bringing the opposing vertical faces of the blocks tightly against the faces of the door and, as the holding element holds the blocks to a distance just equal to the thickness of the door, the door is thus tightly clamped between the blocks. To enable the clamping device to be used on doors of various thicknesses, the holding means is adjustably attached to one of the blocks so that, by adjusting the position of this block relatively to the holding element, the distance by which the blocks are spaced apart may be adjusted. The opposite vertical faces of the blocks which bear against the surfaces of the door may also be provided with a fibrous or resilient facing or pad to avoid marring the surface, in case a polished door is to be held.

Referring, more particularly, to the accompanying drawing, the clamping device comprises a pair of clamping blocks 10 and 12, having vertical faces 14 and 16 at substantially right angles to their lower faces 18 and 20. Longitudinal grooves 22 and 24 are cut in the lower faces 18 and 20 and to the upper face of these grooves is attached a common connecting strap 26 which holds the blocks to each other at a definite distance apart. The strap 26 is of spring steel or other suitable spring material, and is given a slight upward bend at the portion 27 between the two blocks so as to cause the blocks to tilt upwardly about their outer end edges 28 and 30 and cause the inner vertical faces 14 and 16 to diverge upwardly. Accordingly, if a door or other object 32 be inserted between the faces 14 and 16 and permitted to rest on and depress the portion 27 of the spring or holding element 26,

the blocks 10 and 12 will turn on the edges 28 and 30 and be brought against the faces of the door with a force which is much greater than the weight of the door and 5 sufficient to hold the door in position for most purposes.

It will be apparent that to have the blocks tightly clamp the door, the portion 27 of the strap 26 between the blocks must be just the 10 thickness of the door, or in case a tighter clamping effect is desired, just a trifle less than the thickness of the door. To enable the blocks to be so spaced and held as to effectively clamp doors of various thicknesses, the strap 26 is adjustably attached to 15 the block 10 by means of a bolt 34 passing upwardly through a bolt hole 36 in the block and through an elongated slot 38 in the strap 26. The head 40 of the bolt 34 is tightly 20 clamped against the lower face of the strap 26 by means of a thumb-nut 42 threaded on the upper projecting portion of the bolt and bearing against the upper face of a shoulder 44 on the bolt. The strap 26 may 25 be similarly connected to the other block 12, but, as an adjustment for both blocks is ordinarily unnecessary, the strap may be connected to this block by means of screws or 30 rivets 46 or other permanent means. By loosening the thumb-nut 42, the position of the strap 26 on the block 10 may be adjusted and the bolt may be then tightened to hold the block in its adjusted position.

The blocks may be of any suitable form 35 but, in the interest of lightness and strength, they are preferably formed of a flat vertical plate 48, a horizontal plate 50 integral therewith, and of sufficient depth or thickness to receive the groove 24, and of a vertical 40 strengthening rib 52 of substantially triangular form, integral with the face plates 48 and 50. The vertical face plate 48 is preferably widened at its upper end as indicated at 54 in order to distribute the pressing 45 stress at this place. In order to avoid mar-

ring the surface of the door 32, the plate 48 is hollowed or grooved in its outer face to form a pocket 56 in which is placed a pad 58 of resilient material projecting beyond the face of the plate 48. This pad may serve 50 to take up the pressure of the blocks against the surface of the door and thus enable a larger pressure to be obtained than would otherwise be permissible. The faces 14 and 16 have been described and shown as disposed at right angles to the lower faces 18 and 20, respectively, as this is the usual and preferred construction, but it is to be understood that this angle may be varied to suit varying conditions of use. 55

As changes of construction could be made within the scope of my invention, it is desired that all matter contained in the above description or shown in the accompanying drawings shall be interpreted as illustrative 60 and not in a limiting sense. 65

Having described the invention, what I claim and desire to secure by Letters Patent is:

A device of the type described which comprises, a pair of blocks having a lower plate, an upright plate, and a vertical strengthening rib integral with said plates, said upright plates being widened at their upper ends, the bottom faces of said lower plates 70 having aligned longitudinal grooves and being adapted to rest throughout their lengths on a supporting surface, a spring strap member common to said grooves and connecting said blocks in spaced relation to each other 80 and with their opposing edges tilted slightly upwardly, said strap having an elongated slot, a bolt in one of said blocks passing through said slot to adjustably attach said strap to said block, said strap and the head 85 of said bolt being contained in said groove, and a resilient surface on the opposed faces of the upright plates of said blocks.

In testimony whereof I affix my signature.
LEWIS J. BARGER.
